UNITED STATES PATENT OFFICE.

ARTHUR C. CANDLAND, OF PROVO, UTAH.

RAILWAY-TIE AND FASTENER.

1,025,451.

Specification of Letters Patent.

Patented May 7, 1912.

Application filed November 23, 1911. Serial No. 662,067.

To all whom it may concern:

Be it known that I, ARTHUR C. CANDLAND, a citizen of the United States, residing at Provo, in the county of Utah and State of Utah, have invented certain new and useful Improvements in Railway-Ties and Fasteners, of which the following is a specification.

My invention relates to railway ties and fasteners therefor, and my purpose is to provide a cross tie for railways, which is light in weight, easily formed and placed in position and on which a rail may be fastened at any desired place in the longitudinal length of said tie, especially to be used at switches where more than two rails are laid and where various distances are required between rails. These objects I accomplish with the device illustrated in the accompanying drawings in which similar letters of reference indicate like parts throughout the several figures.

Figure 1 is a plan view of the device with a part of a rail on one end. Fig. 2 is a side elevation, one end shown in vertical section on line $\alpha\alpha$, Fig. 1. Fig. 3 is an isometric view of one of the reinforcing members. Fig. 4 is an isometric view of one of the clamps. Fig. 5 is an isometric view of the other clamp. Fig. 6 is an isometric view of one of the locking members. Fig. 7 is an isometric view of the wedge washers.

My tie is cut from a sheet of corrugated metal and bent to form an up-turned channel 1. At the places where the rails are expected to rest the said channel is strengthened by having the reinforcing members 20 secured within the said channel by bolts 2 in the holes 2'; if a tie is to be used at a place in the road where a switch is needed and more than two rails rest on the tie, more than two reinforcements are used and they are placed where the rails cross said channel. Each reinforcing member 20 consists of a sheet of metal bent to the form of the inside of the said channel, and with the central portion thereof crimped upward forming an inverted U-shaped groove 3. Near one end of said groove 3 is cut a transverse elongated slot 4. The horizontal portion, or top, of said groove 3 is extended at one end and is bent vertically upward to form the lock piece 5. Said lock piece 5 has an elongated opening 6 therein. Portions of the sides of said reinforcing members 20 are bent down over the edges of said channel 1, as shown at 7, to form a lock for the sides

of said channel 1 to prevent the said sides from being pushed outward. Another portion of each of said sides of said reinforcing member 20 is not so bent, but is extended upwardly to form shoulders 8. Within each of said reinforcing members 20 is placed a cushion block 9 made of fibrous material to supply the needed cushion effect desired under the rails which rest on said blocks. At one end of said blocks 9 is placed a clamp 10 having an elongated opening 15' therein. A portion 18' of each of said clamps is extended to engage the said shoulders 8 and is also bent to engage the base flange of the rail. On the opposite edge of two of said clamps 10 a lug 11 is integrally formed to fit within said transverse slot 4 in the groove 3. Also within the said slot 4 is fitted a locking member 12 having one edge 19 bent at an angle to engage the under-side of said groove 3. The main portion of said locking member 12 is placed in sliding contact with one of the said clamps 10 and each has an elongated opening 14 therein, the sides 80 of which register with the sides of the similar openings 15 in the said clamps 10. Within said openings 6, 14, 15 and 15' and horizontally through each of the said blocks 9, are fitted two U-shaped wedge washers 16, 85 co-acting when drawn toward each other within said clamps 10 and locking members 12 on one end, and lock piece 5 and the other clamp 10' on the other end, to make the said openings more nearly register.

The corrugations in the sides and bottom of the said channel 1 prevent any lateral movement of the tie on the road bed when ballasted. Where only two rails are to rest on the tie, the said reinforcing members 20, 95 may be riveted firmly in place, and where the switch rails are to be placed, detachable fastenings are used. The shoulders 8 engage the extended part 18 of said clamps as they grip the base flange of the rails, to prevent outward spreading and lateral displacement of the clamps. With the reinforcing members 20 in place within the channel 1, the cushion blocks 9 are then placed within the said reinforcing members 20, one under each rail, with the upper side of said block above the said portion 7 of said reinforcing members 20, which will prevent the rails from contacting with the metal of the reinforcing members 20 or the channel 1. The clamp 10' on the inner side of the track is then placed vertically between

the up-turned lock piece 5 of said reinforcing members 20 and the said block 9. The locking members 12 are placed within the said transverse slots 4, with the angle part 5 19 engaging the under sides of the groove 3 of the said reinforcing members 20, and the clamps 10 for that side of the rail are then placed between the said blocks and said locking members 12 with the lug 11 also 10 within the transverse slot 4 which locks the members 12 in place, the openings 6 and 15' partially registering. The U-shaped wedge washers 16 are then inserted, one from each side, through the said openings 6, 15 13', 14 and 15, with their angled sides contacting, and with the bolts 17 therethrough the nut thereon binds the said lock piece 5, locking member 12, clamps 10, 10' and cushion blocks 9 together, and as will be 20 readily observed any tightening of the nut on the bolt will draw the said clamps downward and inward and firmly grip the base flange of the rail. If other rails are needed as at a switch, other reinforcing members 25 and co-acting elements are secured within the channel 1.

Having thus described my invention I desire to secure by Letters Patent and claim:—

1. A railway tie and fastener consisting 30 of a corrugated open top channel, having closed sides and bottom; detachable reinforcing members carried in said channel each provided with an inverted U-shaped groove extending longitudinally therein and 35 having a transverse slot near the end of said groove; a portion of the sides of said reinforcing members being bent downward to hook over the sides of said channel; up-standing portions forming shoulders on said 40 reinforcing members adjacent said bent down portions; a lock piece formed by the top of said U-shaped groove being extended and bent upwardly at right angles and having an elongated hole therein; clamps 45 adapted to engage the base flange of a rail; detachable locking members each having an elongated hole therein, and a portion bent at right angles and adapted to fit snugly within said transverse slots and to engage 50 with the underside of the said groove in said reinforcing members; and means to detachably secure said reinforcing members in said channel.

2. A railway tie and fastener consisting 55 of a corrugated, open top channel, said channel having closed sides and bottom; detachable reinforcing members carried therein, a portion of the sides of each of said reinforcing members being bent downward to 60 hook over the sides of said channel; another portion provided with an inverted U-shaped groove extending longitudinally therein and having a transverse slot in the top and near the end of said groove; fibrous rail supporting blocks; a lock piece formed by the top of

said U-shaped groove being extended and bent vertically upward and having an elongated hole therein; clamps bent to engage the base flange of a rail, each having an elongated hole therein, said holes partially 70 registering with the holes in said lock piece; detachable locking members each having an elongated hole therein, and having a portion bent at right angles, and adapted to fit snugly within said transverse slots, and to 75 engage the under side of said grooves; U-shaped wedge washers, adapted to fit snugly within the elongated holes within said bent-up lock pieces, said clamps and said detachable locking members; a bolt having a nut 80 thereon adapted to fit within said U-shaped wedge washers, with the head of said bolt engaging with the larger end of one of said washers, and the nut on said bolt engaging with the larger end of the other of said washers, and adapted to force said washers along each other, and thereby cause the partially registering elongated 85 holes in said lock piece, locking member, and said clamps to more nearly register, and thereby bind the said clamps against the 90 base flange of the rail.

3. A railway tie and fastener consisting of an open topped channel; reinforcing members detachably fastened therein; provided 95 with an inverted U-shaped groove longitudinally formed in each with a transverse slot in said groove; locking members each having a portion thereof bent to engage the underside of said U-shaped grooves, and 100 fitted within said transverse slots; clamps having one edge bent to grip the base flange of a rail; a lug on the lower side of said clamps adapted when in said transverse slots to prevent the withdrawal of the said 105 locking members from said slots; cushion blocks fitted between said clamps, and each having a horizontal opening therethrough; U-shaped wedge washers, slidably movable on each other, and within the elongated 110 openings in said locking members and said clamps; and means to drive said wedges in longitudinally opposed directions, said means consisting of a bolt, with a threaded nut thereon adapted to drive one of said 115 washers in one direction, and the other simultaneously in the opposite direction.

4. A railway tie and fastener consisting of an open topped channel; reinforcing members detachably fastened therein provided with an inverted U-shaped groove 120 longitudinally formed therein with transverse slots in said groove; a lock piece integrally formed on the end of each of said reinforcing members and having an elongated opening therein; clamps having one edge bent to engage the base flange of a rail, and an elongated opening in each; cushion blocks fitted between said clamps, and having a horizontal opening therethrough; U- 125

shaped wedge washers slidably movable on each other, and within said elongated openings in said lock pieces and said clamps; and a bolt with a threaded nut thereon 5 adapted to drive one of said washers in one direction, and the other simultaneously in the opposite direction.

5. A railway tie and fastener consisting of an open channel; reinforcing members 10 detachably fastened therein, having an inverted U-shaped longitudinally formed groove with a transverse slot in the top and near one end thereof; a lock piece formed by the top of said U-shaped groove, being extended and bent upwardly at right angles, and having an elongated hole therein, locking members each having a portion thereof bent to engage the under side of said U-shaped grooves and to fit within said trans- 15 verse slots; clamps bent to engage the base flange of a rail each having an elongated hole therein, said holes partially registering with the holes in said lock pieces; other clamps bent to engage the base flange of a rail, and having similar holes therein, partially registering with the holes in said locking member; fibrous rail supporting blocks having a horizontal opening through each, fitted between said clamps; U-shaped 20 wedge washers slidably movable on each other, and within said elongated openings in said lock pieces, locking members, and clamps; and means to drive said wedges in longitudinally opposed directions.

35 6. A railway tie and fastener consisting of a channel having an open top; reinforce-

ring members detachably fastened therein and provided with an inverted U-shaped groove extending longitudinally in each with a transverse slot in said groove, a portion of the sides of said reinforcing members being bent down over the sides of said channel; upstanding portions of the sides of said reinforcing members adapted to form shoulders thereon adjacent said bent down portions; fibrous rail supporting blocks in said reinforcing members; a lock piece integrally formed on an extended portion of each of said reinforcing members, each of said lock pieces having an elongated opening therein; 40 a locking member having a portion thereof bent to engage the under side of one of said grooves and adapted to fit within one of said transverse slots, and provided with an elongated perforation; clamps bent to engage the base flange of a rail, each provided with an elongated perforation, partially registering with the perforation in said locking member when said clamp and said locking member are adjacent; U-shaped wedge 45 washers within said elongated perforations; and a bolt with a nut thereon adapted to drive one of said washers in one direction, and the other simultaneously in the opposite direction and thereby to draw said clamps 50 toward the rail and downward.

In testimony whereof I have affixed my signature in presence of two witnesses.
